UNITED STATES PATENT OFFICE.

WILLIAM ROSE, OF GAINSBOROUGH, ENGLAND.

BAG-MAKING MACHINE.

1,271,519.

Specification of Letters Patent.

Patented July 2, 1918.

Application filed July 29, 1916. Serial No. 112,167.

To all whom it may concern:

Be it known that I, WILLIAM ROSE, a subject of the King of Great Britain, residing at Albion Works, Gainsborough, in the 5 county of Lincoln, England, have invented new and useful Improvements in Bag-Making Machines, of which the following is a specification.

The object of this invention is to provide 10 improved apparatus for folding, and applying adhesive matter to the ends of bags, or the like, (I will refer to them as bags) more especially intended for use in connection with bag-making machines.

15 For the purposes of description I will presume that the formers are in a horizontal position and that the outermost end of the bag, or the like, is being closed, although the formers may be in other position if 20 desired.

The end of the bag is first folded on one side, and then on the opposite side, so that the outstanding portions, or ears, are left which are triangular, or approximately so.

25 Adhesive matter (which I will refer to as gum) is then applied to the folded down portions and afterward the outstanding portions are folded and pressed onto the preceding gummed folds; the end of the 30 bag being completely folded and gummed while in one position.

The partly made bag may be placed on a former by hand, in position to be operated upon, or it may be brought into position by 35 any suitable mechanism, or the former may be in connection with any type of bag-forming machine wherein a former is, or formers are, employed.

I will describe this invention with reference 40 to the accompanying drawings in which Figure 1 is a side elevation, Fig. 2 an end elevation, looking in the direction of the arrow A Fig. 1, and Fig. 3 a plan of folding and gumming devices in accordance with my invention. Figs. 4 and 5 are elevations at right angles to each other, drawn to a larger scale than that to which 45

Figs. 1, 2 and 3 are drawn and showing more clearly the first folder, side folders 50 and the gumming device. Fig. 6 is a section on the line C. D. Fig. 4. Figs. 7, 8, 9 and 10 are views showing successive positions of the gumming device when a bag is on a "former." Fig. 11 is a similar view 55 to Fig. 10 but showing the gumming device in the position which it occupies when

the "former" is not provided with a bag. Figs. 12 and 13 are views showing more clearly the means controlling the gumming device. 60

The first fold is made by means of a folder 1, capable of turning on a center, for instance, on the shaft 2, this folder being shaped to crease, and splay out, the remaining outstanding portions of the bag so 65 that proper following folds are made. The opposite side is then folded down by a second folder 3 capable of turning upon a center preferably by being mounted on the said shaft 2 on which the first folder 1 is 70 mounted and operated by mechanism (such as cams and levers, or the like, say from the main shaft of the machine as hereinafter described) such that after the second fold has been made the folder 3 will remain stationary on the end of the bag while other 75 folders 4 and 5 are caused to press the outstanding portions onto the folder 3 in order to properly crease the said portions. The folders 4 and 5 are then moved sufficiently 80 away from the bag to enable the folder 3 to continue its forward movement and a gumming device 6 is then caused to apply gum to the folded down portions, the said gumming device being preferably carried by a 85 frame 7, mounted on the arm of the folder 3. When the folder 3, and the gumming device 6, have moved clear of the bag the 90 folders 4 and 5, which creased the upstanding portions as aforesaid, are again brought 95 into operation to fold down, and press, the said portions onto the gummed portions and the end of the bag is then completely folded. 100

The gumming device 6, is preferably so shaped that it will apply gum to the first two folds over a surface corresponding in shape, or approximately corresponding in shape, to the outstanding portions, or ears, to be folded down thereon. The said gumming device 6, may be operated by any suitable gearing arranged so that before the folder 3, commencing to move in a direction to operate upon the bag the gumming device 6, will take gum from a roller 8, rotating in a bath 9, of gum, while when the folder 3, is moving in the opposite direction it will not come into contact with the gumming roller 8. This may be effected by the cam 29, hereinafter referred to, being so shaped as to turn the device 6 105 (through the hereinafter described gearing 34, 35, 36) before it descends into a position 110

such that it passes down clear of the roller 8. In order that the gum may be properly applied, the gumming device 6, should roll upon the surface being gummed and this movement can conveniently be effected by a roller 9^a, mounted on the frame, or carrier, 7, of the gumming device and operating upon a stationary cam, 10.

Means may be provided to insure that if a bag be not upon a former X the gumming device 6, when making its forward movement, shall not apply gum to the said former. Any suitable means may be employed for effecting this but I preferably employ the following means:—Mounted on the spindle 11, which carries the folder 5, is an arm 12, yieldably connected to the said folder by a spring 13, having a part 14, projecting through the folder 5, and arranged to be operated so that, if a bag be not in position on a former, the said arm 12, not being restrained from entering opening 54 by a bag on the former, will be in such a position as to cause another arm 15, to be brought into the path of a stop 16, on a second cam 17, so as to arrest the movement of the said cam 17. The roller 9^a, mounted on the frame, or carrier, 7, of the gumming device 6, then acts on the second cam 17, instead of on the stationary cam 10, and the gumming device 6, is caused to take a path clear of the said former without a bag so that no gum is applied to the said "former." When however there is a bag on the said "former" the projection 14, on the arm 12, which is yieldably connected with the folder 5, as aforesaid, will come into contact with the bag and the cam 17, will not be arrested but will continue its movement and enable the roller 9^a, of the gum-applying device 6, to operate upon the stationary cam 10, as hereinbefore described.

The various operating parts may be actuated by any suitable arrangement of gearing, cams, and levers, or the like, from the main shaft 18, or any suitable part, of the machine. In the drawings the parts are shown as being operated by the means hereinafter described, but I do not limit myself to the use of these precise means.

50 The folders 1 and 3 are caused to oscillate on the shaft 2, respectively by cams 19, and 24 (respectively acting in opposition to the springs 19^a and 24^a) secured to the main shaft 18, which, through antifriction rollers 20, and 25, actuates bell-crank levers 21, and 26, respectively connected by the rods 22, and 27, to projecting arms 23, and 28, of the folders 1 and 3 respectively.

55 The gumming device 6, is carried, as hereinbefore mentioned, by the folder 3, and oscillates therewith, but, in order to take up the gum and to apply it to the bag, the device 6, is also caused to oscillate on its pivot 3^a, this being effected by the cam 29 (acting 60 in opposition to a spring 29^a) secured to the

shaft 18, which actuates, through an antifriction roller 30, a bell-crank lever 31, connected by a rod 32, to a projecting arm 33 of a segmental rack 34, in gear with a toothed wheel 35, which gears with a toothed wheel 36, formed in one with the gumming device 6. The roller 8, which supplies gum to the device 6, is rotated, at the proper time at the same peripheral speed as the said device 6, by a cam 38, (acting in opposition to a spring 38^a) secured to the shaft 18, which actuates, through an antifriction roller 39, a bell-crank lever 40, connected by a rod 41, to an arm 42, carrying a pawl 43, which acts upon a ratchet 44, secured to the said roller 8.

55 The folder 5, is oscillated on the spindle 11, by a cam 46, (acting in opposition to a spring 46^a) secured to the shaft 18, which actuates, through an antifriction roller 45, a bell-crank lever 47, connected by a rod 48, to a projecting arm 49, of the said folder 5, and this movement is transmitted to the folder 4, by a toothed segment 50, in one with the folder 5, which engages with a toothed segment 51, in one with the folder 4.

95 The arm 12, is free on the spindle 11, of the folder 5, and it is caused to move with the said folder toward the bag by the connecting spring 13, which tends to keep projections 52 and 53, on the tails of the folder and arm respectively, in engagement until the projecting part 14, of the arm is brought into contact with the bag which then prevents any further forward movement of the 100 said arm. The folder 5, thereafter continues to move forward and presses, or creases, the folds of the bag onto the folder 3, in readiness to receive gum from the device 6, which is operated during the upward movement of the said folder 3. If, however, the "former" X, be without a bag, the projecting part 14, enters a recess 54, in the folder 3, so that the said arm and folder 5, move together until the folder 5, comes into contact with the said folder 3. The further movement of the arm 12 (which is permitted by the absence of the bag) causes a projection 55, on the said arm to come against a 105 projection 56, on the before-mentioned arm 15, and thereby move this arm into the path of the stop 16, on the cam 17, so that when the said cam turns on its pivot 2, with the folder 3, its movement is limited by the stop 16, engaging with the arm 15, and upon the 110 arm of the folder 3, continuing its upward movement, the roller 9^a, engages with the said cam 17, (which is of larger diameter than the cam 10) and the frame 7, is thereby 115 caused to turn so that the device 6, clears the former X when the said device has been brought to approximately the position in which it applies the gum.

120 The cam 17, is yieldingly connected to the arm of the folder 3, by a spring 57, which 125

keeps stops 58, and 59, on the said cam and folder, respectively, normally in contact.

The arm 15, is caused to move out of the path of the stop 16, by the projection 55, 5 upon the return of the folder 5, engaging with another projection 60, on the arm 15.

Although I have described this invention as applied to a bag-forming machine it is not limited to such application.

10 What I claim is:—

1. In apparatus for folding and applying adhesive matter to the ends of bags, or the like, the combination of a side folder turnable on a center for folding down the first fold, and shaped to crease and splay out the outstanding portions of the bag end, a second turnable side folder for folding down the opposite side of the bag end and temporarily holding it down, end folders movable 15 to crease the outstanding portions or ears of the bag end against the second folder while it remains temporarily in holding-down position, means independent of the folders for applying adhesive after the second side folder has moved from holding-down position, and means for completing 20 the movement of the end folders to fold

down the end ears upon the side folds to complete the bag closure.

2. In apparatus of the construction specified in claim 1, the mounting of the adhesive applying device on the arm of the second side folder. 30

3. In apparatus of the construction specified in claims 1 and 2, the combination therewith of an adhesive supply roller, with which the applying device comes in contact on the forward stroke of the second side folder, and means for preventing such contact on the return stroke of said folder. 35

4. In apparatus of the construction specified in claim 1, the combination therewith of means associated with the end flap folders for preventing the operation of the adhesive applying device unless a bag blank be 40 upon the former. 45

In testimony whereof I have signed my name to this specification in the presence of two subscribing witnesses.

WILLIAM ROSE.
